ATTORNEYS

UNITED STATES PATENT OFFICE.

FRANK J. NOVAK, OF SOUTH OMAHA, NEBRASKA.

DESIGN FOR A COLLAR.

No. 37,863.

Specification for Design.

Patented Feb. 27, 1906.

Application filed August 29, 1905. Serial No. 276,310. Term of patent 14 years.

To all whom it may concern:

Be it known that I, FRANK J. NOVAK, a citizen of the United States, residing at South Omaha, in the county of Douglas and State of Nebraska, have invented a new, original, and ornamental Design for Collars, of which the following is a specification, reference being had to the accompanying drawing, forming part thereof.

The figure is a plan view of a collar, showing my new design.

I claim—

The ornamental design for a collar as shown.

FRANK J. NOVAK.
